GUIDED MISSILE

William Hunter A. Boyd, Kensington, Md., assignor to
the United States of America as represented by the
Secretary of the Navy

Application May 6, 1949, Serial No. 2,502

Term of patent 14 years

(Cl. D71—1)

FIG. 1

FIG. 2

FIG. 3

FIG. 4

Fig. 1 is a perspective view of a guided missile as it appears when seen obliquely from above and at the front;

Fig. 2 is an inverted perspective view of the guided missile when seen from a position below and at the front;

Fig. 3 is a perspective view of the guided missile as it appears when seen obliquely from above and at the rear, and

Fig. 4 is a side elevation of the guided missile.

The design for a guided missile is characterized by the superstructure on the payload, and the tapered, swept-back wings that project from its sides virtually flush with the top surface thereof and, further, by the empennage under the aft end of the payload component and the shroud ring.

What is claimed is:

The ornamental design for a guided missile, substantially as shown and described.
